5 Claims. (Cl. 73—35)

The present invention relates to a structure for reducing noise generated by an explosion. More particularly, this invention relates to an improved noise-reducing structure having an increased load limit for explosive charges detonated therein.

The prior art has disclosed structures which may be reused a great many times in testing explosives and which also effectively control and modify the noise created by such explosives testing so that the noise no longer is objectionable in the area outside the structure. More recently, interest in such noise-reducing facilities has increased because of the expanding use of explosives in non-disruptive operations such as metal forming and processing. Frequently, both the testing and the routine use of explosives in metalworking advantageously can be carried out close to other facilities; however, these facilities must be protected from missiles arising from the explosion and from blast effects, and the occupants must be protected from objectionable noise associated with the use of explosives.

Principles governing the design of such protective structures have been disclosed. U.S. Patent 2,940,300 teaches that a relationship has been developed which permits calculation of the value of the equivalent hydrostatic pressure which will be generated by detonation of an explosive charge within the protective structure. The patent discloses that the pressure generated is dependent on the kind and weight of the explosive charge and on the volume enclosed by the structure as follows:

$$P = K \frac{W}{V}$$

in which P is the equivalent hydrostatic pressure in pounds/square inch which must be contained without exceeding the permissible strain on the structure, K is a constant characteristic of the explosive being used, W is the weight of the explosive in pounds, and V is the volume in cubic feet enclosed by the structure.

In accordance with the above relationship, reduction in V , the volume, enclosed by a given structure must be compensated by a reduction in the weight of a given explosive which may be detonated without exceeding a given equivalent hydrostatic pressure, P . Conversely, the weight of the explosive charge which may be detonated without damaging the enclosing structure cannot be increased without a proportionate increase in the volume of a structure having given strength characteristics. Frequently, however, there is a desire or a need to increase the weight of explosive charge to be detonated in an existing structure. Likewise, there is a desire to minimize the size and cost of a noise-reducing structure designed to be erected in accordance with the principles known heretofore.

I have found that the presence of a substantial mass of loose granular material occupying a segment of the structure permits a greater loading of explosive per unit of

2

structural strength of the structure than is permissible for the empty structure itself. Accordingly, this invention provides a noise-reducing structure which comprises a chamber, said chamber having walls of sufficient mass and tensile strength to withstand the equivalent internal hydrostatic working pressure, P , in pounds/square inch, in accordance with the equation:

$$P = K \frac{W}{V}$$

wherein K is an empirical constant depending upon the explosive used, W is the weight of the explosive in pounds, and V is the volume of the empty chamber measured in cubic feet; a closable access means into said chamber; a noise-muffling gas-venting means emanating from said chamber; and a mass of loose granular solid occupying a segment of said chamber, the height of said segment being about $\frac{1}{24}$ to $\frac{1}{2}$ of the height of said chamber.

The shape and construction of the substantially closed noise-reducing chamber will depend on a variety of factors. Desirably, the structure will be free of sharp angular joints which lead to localized concentrations of stress. The preferred design is defined as a chamber, or structure, having a pair of opposed hemispherical ends which are joined to each other and form a spherical chamber, or are joined to a tubular center section to form a cylindrical chamber with rounded ends. In the latter case, the structure may be positioned with its longitudinal axis either horizontally or vertically, the horizontal position being preferred.

The structure may be made of any material having relatively high tensile strength and resistance to brittle fracture under the conditions of use. However, considerations of cost, availability, ease of fabrication, and strength characteristics generally dictate the use of steel as a material of construction. Especially preferred are steels of Type T-1 made by the United States Steel Corporation and ASTM Types A-212B and A-201. The structure may be made of a single thickness of steel or may be a sandwich construction consisting, for example, of two sheets of steel and an interposed layer of concrete. In all constructions, the walls of the shell must be capable of withstanding the complex pressure pulse developed by the detonation of the explosive charge within the chamber. The strength of the wall required to withstand the pressure pulses generated by detonation of an explosive within the structure is a function of the volume of the chamber, the kind of explosive detonated, the weight of the explosive which is detonated, and the yield strength of the material of which the chamber is constructed.

The empirical expression

$$P = K \frac{W}{V}$$

55 which defines the equivalent hydrostatic pressure generated by detonation of an explosive charge within the noise-reducing structure, was derived from measurements of structural deformation generated by detonating various explosives in the center of chambers of several sizes and shapes, as described in Industrial and Engineering Chemistry, volume 49, pages 1744-1746 (1957). The constant K used in this expression depends not only on the strength of the explosive but also on the completeness of reaction for the explosive decomposition under

the conditions which prevail in the noise-reducing chamber. Thus, the value of K equals 2×10^4 for trinitrotoluene (TNT), 1.5×10^4 for pentaerythritol tetranitrate (PETN), and 7×10^3 for 40% dynamite.

Although PETN has a higher available explosive energy per unit weight (1300 kcal./kg.) than does TNT (about 860 kcal./kg.), a higher value of K is used for TNT than for PETN because of the reaction with air of the initial detonation products of highly oxygen-deficient TNT. The rather low K for the 40% dynamite is ascribed at least in part to the incomplete reaction of the ingredients in the absence of a high degree of confinement such as prevails under the usual conditions of use in a borehole.

The values of K given above have been corrected to allow for dynamic loading but contain no safety factor. A safety factor, however, is included in the calculations which were used in establishing the maximum permissible weight of an explosive to be detonated in a noise-reducing structure of the prior art.

The permissible equivalent hydrostatic pressure, P , was established on the same basis as is used for determining the maximum working pressure for conventional pressure vessels. Thus, for a spherical vessel, the A.S.M.E. Boiler and Pressure Vessel Code, Section VIII, Subsection C, 1959 Edition, p. 79, Table UCS-23, specifies for a typical structural steel (S-201 A) a maximum allowable stress of 13,750 pounds per square inch which is 25 percent of the specified minimum tensile strength of this alloy. Said maximum allowable stress in the wall of a spherical vessel will produce a strain (measurable with conventional strain gages) of 310 microinches per inch, in accordance with standard methods of stress analysis (see Timoshenko, S. and Woinowsky-Krieger, S., "Theory of Plates and Shell," Second edition, page 482, McGraw-Hill Book Co., New York, 1959). Hence, a measured maximum strain of about 310 microinches per inch was accepted as the permissible strain limit in a structure made of the specified steel, and the permissible explosive-load limit, correspondingly, was that weight of explosive which produced the permissible limit strain in the noise-reducing sphere. A series of such strain measurements relating the volume of a noise-reducing structure, the permissible strain limit, and the weight of the explosive which was detonated established a value for " K " which was characteristic for each given explosive.

Having thus experimentally established the relationship,

$$P = K \frac{W}{V}$$

and determined values of K for several common explosives, said relationship was usable in the design of noise-reducing structures of other sizes, shapes, and other materials of construction. Use of the relationship also permitted calculation of permissible load limits for different explosives in any given noise-reducing structure, and also the strain to be expected in a given structure upon detonation of selected explosive charges.

The accompanying FIGURE 1 depicts, partially in section, a particularly preferred embodiment of this invention. In this figure, 1 represents the steel shell, spherical in shape; 2 represents an access door, preferably inwardly opening; 3 represents a supporting cradle, also of steel; 4 represents a supporting base, for example, reinforced concrete; 5 represents a steel vent-tube welded to the shell and connected to a gas muffler 6 by flanges 7 which have between them a steel grating 8 which supports the filling of lightweight chain 9 which provides a devious path for the explosion gases as they pass through muffler 6. Inside the shell is a layer of dense granular or particulate material 10, for example sand or crushed limestone. Not shown are retaining hooks welded to shell 1 to position explosive charges within the shell and electrical conduits for ignition circuits and instrument circuits. Additionally, other openings with suit-

able closures may be included for making photographic studies, for forced ventilation, and the like.

The use of sand as the granular material has been indicated because of its ready availability, low cost, and relatively high bulk density of about 100 pounds/cubic foot. However, other loose granular or particulate materials having a bulk density of 40-280 pounds/cubic foot may be used instead of sand, as for example, soil, crushed limestone, crushed rock, granulated salt, crushed barite, and the like. Desirably, all materials used in this manner will be noncombustible. While the size of the particles is not critical, I prefer to use a loose granular material composed of a blend of particles, all of which are held on a No. 100 sieve (0.0058-inch opening) and all of which pass a sieve having a $\frac{3}{4}$ -inch opening.

While positioning of the granular material in other locations may be feasible, I prefer to place the granular material in the bottom of the structure where it can be used as a support for the explosive-bearing assembly and where gravitational forces will keep the material in substantially a fixed and uniform location.

To minimize the creation of undesirable noises in venting the explosion-generated gases from the chamber, a muffling device preferably is incorporated in the vent. In the specific structure illustrated, chain in a cylindrical housing is used to create a devious path for the gases. Any other arrangement such as is conventional in the sound muffling art to provide a devious path for the gas flow and to attenuate the sound may be used.

FIGURE 2 illustrates the strain-time relationships which resulted from detonations within a noise-reducing structure of FIGURE 1 when empty and when different amounts of loose granular solid were present, as described in Example 1.

The following examples are given to further illustrate the instant invention.

Example 1

A 12-foot sphere was made having a shell wall of $\frac{3}{4}$ -inch-thick steel, an access opening approximately 5 feet high and $2\frac{1}{2}$ feet wide located approximately halfway between the bottom and top of the sphere and fitted with an inwardly opening door, and mounted on top of the sphere a muffler comprising an 18-inch-diameter by 4-foot-long steel cylinder having a steel support grating between the sphere and the lower end of the cylinder, the space above the grating being substantially filled with a packing of lightweight chain. The sphere was supported in a steel cradle on a concrete base. Calibrated strain gages were mounted on the external surface of the sphere to measure the strain, i.e., the deformation per unit length produced in the steel shell by the detonation of 12-pound charges of TNT suspended substantially in the middle of the sphere. The gages were connected to an oscillograph which made a record of the variation in displacement with time. By use of a calibration factor, the displacement was expressed as strain in microinches/inch. Measurements were made both before and after placing sand in the spherical structure, with results as shown in FIGURE 2 and in the table below.

FIGURE 2 shows that the maximum strain (M) in the empty spherical structure (graph A) occurred a few milliseconds after the initial pressure pulse (I). In the presence of a 1-foot segment of sand, however, the maximum strain (M) was reduced (graph B). With approximately a 2-foot segment of sand in the sphere (graph C), the maximum strain coincided with the initial strain. This amount of sand therefore represents substantially the optimum quantity, i.e., the quantity of sand which permits detonating maximum charges of explosive without exceeding the permissible strain on the sphere. The segment occupied by loose granular material can be increased to a thickness equal to one-half the height of the sphere before the reduction in volume is such that the initial strain, which in this case also is the maximum

strain, reaches the level of the maximum strain produced by detonation of an equivalent charge in the empty spherical structure. The numerical data corresponding to the strain graphs of FIGURE 2 are shown in the table below.

Graph	Height of Sand Segment in Feet	Percent of Spherical Volume Occupied by Sand	Initial Strain (I) in Micro-inches/inch	Maximum Strain (M) of Steel Sphere in Micro-inches/inch
A-----	0	0	79	168
B-----	1	2.0	80	138
C-----	2	7.4	114	114

The marked reduction in the maximum strain of the steel sphere was accomplished in spite of a reduction in the free volume of the sphere and without hampering or minimizing the noise-reducing capability of the spherical structure.

Hence, reduction of maximum strain of the spherical chamber is achieved when from $\frac{1}{24}$ to $\frac{1}{2}$ of the height of the chamber is occupied by loose granular material, a preferred quantity being a segment of height equal to $\frac{1}{12}$ to $\frac{1}{4}$ the height of the chamber.

Example 2

This example illustrates the reduction in strain which is attained when an explosive-containing assembly is detonated directly on a mass of sand inside the noise-reducing structure, instead of being suspended in the free space above the sand.

Amatol was spread uniformly over the surface of a 1-foot x 5-foot rectangular metal plate resting on the surface of a 2-foot-high segment of loose sand contained in the spherical noise-reducing structure described in Example 1. The explosive was detonated and the resulting strain in the steel structure was measured. The measured strain was much less than that expected on the basis of previous experience and of design principles previously disclosed, as shown in the table below.

Explosive		Maximum Strain (microinches/inch)	
Kind	Weight, lb.	Calculated	Measured
50/50 Amatol	1.85	34	25
80/20 Amatol	4.56	84	42
80/20 Amatol	17.44	320	150

The 17.44-pound amatol charge represents about the maximum which can be detonated in the given empty spherical steel structure without exceeding the permissible strain. With the sand in the sphere, however, the strain is only about half that anticipated, and hence a much larger explosive charge can be detonated on the mass of loose sand without exceeding the permissible strain of approximately 310 microinches/inch.

Another desirable feature of the improved structure of this invention also is illustrated in this example, viz., the explosives-bearing assemblies can rest on the sand base rather than having to be suspended or mounted near the center of the sphere in order to distribute the strain and avoid local concentrations on limited areas of the internal surface of the structure.

The discovery that the presence of a substantial mass of a loose granular material permits a greater loading of explosive per unit of structural strength is most surprising, particularly since the volume of the structure is considerably reduced and the pressure resulting from the detonation varies inversely with the volume of the structure. While I do not wish to be bound by any theory concerning the beneficial effects of the mass of granular material, I believe the explanation is that in any empty or

substantially empty structure the maximum strain on the structure walls does not come with the initial shock wave resulting from the detonation of the explosive but rather occurs when reverberation by internal reflection of the initial shock wave combines reinforcingly with resonance of the structure. The presence of the mass of loose granular material apparently reduces both the resonance and the reverberation, perhaps by energy absorption, and therefore reduces the maximum strain. If less than $\frac{1}{24}$ of the height of the structure is occupied by loose granular material, very little reduction of maximum strain is achieved. On the other hand, when more than $\frac{1}{2}$ of the height of the structure is occupied by loose granular material, the reduction in volume results in pressures great enough to overcome the moderating effects of the loose granular material so that the initial pressure pulse imposes as much strain as would be a delayed but reinforced pulse created by detonation of the given explosive charge in an empty structure. When about $\frac{1}{6}$ the height of the structure is occupied by loose granular material, an optimum reduction of stress on the structure walls is achieved.

Although the specific embodiments described above may be modified within the scope of my invention, the invention is not to be limited except as defined in the following claims.

What is claimed is:

1. A noise-reducing structure comprising a chamber within which explosives are detonated, said chamber having walls of sufficient mass and tensile strength to withstand an equivalent internal hydrostatic working pressure, P , in pounds/square inch, in accordance with the equation

$$P = K \frac{W}{V}$$

wherein K is an empirical constant dependent upon the explosive used, W is the weight of the explosive in pounds, and V is the volume of the chamber measured in cubic feet; a closable access means into said chamber; gas-venting means emanating from said chamber; and a mass of loose granular solid contained within said chamber.

2. A noise-reducing structure comprising a chamber within which explosives are detonated, said chamber having walls of sufficient mass and tensile strength to withstand an equivalent internal hydrostatic working pressure, P , in pounds/square inch, in accordance with the equation

$$P = K \frac{W}{V}$$

wherein K is an empirical constant dependent upon the explosive used, W is the weight of the explosive in pounds, and V is the volume of the enclosed chamber measured in cubic feet; a closable access means into said chamber; gas venting means emanating from said chamber; and a mass of loose granular solid occupying a segment of said chamber, the height of said segment being about $\frac{1}{24}$ to $\frac{1}{2}$ of the height of said chamber.

3. The structure of claim 2 wherein the chamber is spherical.

4. The structure of claim 2 wherein the chamber is tubular with hemispherical extremities in concave relation to each other.

5. The structure of claim 2 wherein said granular solid material is sand.
